CIGAR LIGHTER

Louis V. Aronson, Newark, N. J., assignor to Art Metal Works, Inc., a corporation of New Jersey

Application June 3, 1927, Serial No. 196,255

31 Claims. (Cl. 67—7.1)

The invention relates to cigar lighters or the like and the main object of the invention is to provide a more efficient and convenient form of lighter than has hitherto been produced.

5 Further objects of the invention will appear from the following description when read in connection with the accompanying drawing showing an illustrative embodiment of the invention and wherein:

10 Fig. 1 is a side elevation;

Fig. 2 is an edge view with the parts in the position occupied while the wick is ignited;

Fig. 3 is a central vertical section on line 3—3 of Fig. 4;

15 Fig. 4 is a vertical section on line 4—4 of Fig. 3, Figs. 3 and 4 showing the apparatus in closed position; and

Fig. 5 is a plan view.

As shown the device comprises a receptacle 10 having a bottom wall 11 and a top wall 12, the bottom wall being provided with a filling opening 13, shown as closed by means of screw plug 14, the knurled head of which desirably seats and is countersunk in a recess in the thickness of the

25 wall 11.

To support a wick 15 projecting from the top of the receptacle 10 there is shown a wick tube 16 mounted upon the top wall 12, the tube 16 being shown as provided with an opening 17 for insertion of a pin into the wick for adjusting the height thereof.

To provide sparks for ignition of the material with which the wick 15 may be saturated, there is shown a pyrophoric element 18 projecting 35 from a tube 19 passing through the wall 12 and through the receptacle and opening through the bottom wall 11. The axis of the tube 19 is curved in passage through the receptacle as shown in Fig. 3 in order to bring the pyrophoric member

40 18 toward the center of the top of the receptacle and beneath an abradant wheel 24. The element 18 may be spring-pressed outwardly and into engagement with the wheel 24 by the influence of a coil spring 20 embracing a piston 21

45 at one end and a screw plug 22 at the other end which screw plug has engagement with the opening of the tube 19 and the knurled head 23 of which seats and is countersunk in a recess in the wall 11 symmetrically with the head 14. The

50 curvature of the spring tube 19 furthermore permits the pyrophoric element 18 to engage the sparking wheel in a direction perpendicular to a tangent running to the base of the wick and at the same time the curvature of the tube permits the thumb screw 23 to be located with its

thumb portion flatwise of the bottom of the casing and at a position symmetrical on the casing with respect to the thumb button 14.

To provide sparks for ignition of fuel carried by the wick 15, there is shown an abradant wheel 24 journaled about a horizontal axis on top of the receptacle and mounted on a shaft 25 journaled in upstanding ears 26, 27 projecting from the wall 12. The ears 26, 27 are integral with the sides of the receptacle and extend upwardly 10 from the top thereof.

To cause revolution of the wheel 24, there are provided pinions 28, 29 freely journaled on the shaft 25 in mesh with racks 30, 31 carried by the arms 32, 33 of a U-shaped member rigidly supported for sliding movement upon a tubular member 34 projecting and telescoping and sliding into a tubular member 35 passing through the top wall 12 and extending into the interior of the receptacle. To eject or force said member 34 20 forwardly to normal position, there is shown a coil spring 36 housed within the member 34 and seating upon the bottom wall 37 of the tubular member 35.

If desired, as shown, the rack members 32 and 25 33 may be made integral with each other and with the thumb button 48 so as to provide a rugged construction not likely to get out of order. It will be observed that the thumb button, together with the rack members and connected 30 portions, are securely held against turning about the axis of the plunger or tubular member 34 by reason of the engagement of the rack members with the edges of the ear members 26 and 27. The rack members are further guided and held 35 in proper alignment against bending or jamming by reason of the fact that the two rack members embrace the sides of the guard member 40, which in turn closely embraces the sparking wheel.

The pinions 28, 29 are shown as rigidly secured 40 to the side members 38, 39 of a member also journaled upon shaft 25 and carrying a shield or guard 40 for covering the abradant surfaced wheel and also carrying a snuffer 41, seating in its closed position, upon wick tube 16 and covering the projection of the wick.

For transmitting the motion of the member 38, 39, 40, to the abradant wheel 24 in one direction of its movement, there is shown a pawl 42 pivoted at 43 upon the member 39 and pressed by means 50 of a spring 44 into engagement with ratchet teeth 45 carried by the wheel 24. Thus the snuffer is journaled on the same horizontal axis as the wheel 24 and the snuffer has thereon gear members 28, 29 meshing with racks 30, 31 on the man-

5

50

55

ually pressible member 48 and a ratchet member 45 on the wheel is engaged by a pawl 42 carried by the snuffer, so that both the snuffer and abradant wheel are actuated by manual pressure.

5 A cover or cap plate 46 is secured to and over the upper wall 12 and beneath the wheel 24 having openings through which the wick tube 16, the pyrophoric element, tube 19, member 34, and the member 35 extend respectively. The cap plate 46 is shown retained in place as by means of a screw 47. As shown in the drawing, the cap plate 47 has a depending flange extending about the upper edge of the receptacle.

The exterior of the casing 10 may be covered 15 with suitable leather or fabric covering as shown, secured by adhesive or otherwise, and the over-hanging flange on the cap plate 46, as well as the corresponding flange on the bottom plate 11, serves to protect the edges of such covering material and prevents the same from being peeled off 20 from the metal container.

The device may be operated by the pressure of a finger or thumb upon the head 48 of the sliding member 34, thus manually pushing down the 25 member 34, compressing the spring 36, depressing the racks 30, 31 so as to lift the snuffer 41 and through the medium of the pawl 42 to revolve the wheel 24 and to throw sparks for ignition of the fuel carried by the wick. The head portion 30 48 as integrally formed with the top of the plunger or tubular member 34 and the portions 32 and 33, may be conveniently termed as a thumb or finger piece member. Thus the snuffer and abradant wheel 24 are actuated by manual pressure. The pressure is maintained upon the member 48 while the flame is utilized and upon release 35 of the pressure, the snuffer returns to place upon the wick to extinguish the flame.

It will be observed that with the construction 40 above described, a lighter is provided in which the operating thumb piece and the snuffer cover present a generally similar external appearance and are substantially symmetrically located in respect to the top of the lighter, thereby making possible 45 a lighter of not only enhanced appearance but of a shape which may be readily gripped and operated by the user with one hand and yet having no unsymmetrical or protruding operating parts which might interfere with rapid manipulation or make the lighter inconvenient to carry in 50 one's pocket.

It will be further noted that a compact and durable arrangement of the snuffer cap carrying member, the sparking wheel, ratchet, and rack 55 and pinion members is provided. This compact arrangement not only eliminates waste space but enables each of the various parts to contribute to the support, strengthening and guiding of the other parts. The snuffer carrying member provides not only a guard for the sparking wheel, 60 but a cover largely concealing the ratchet and preventing the same from catching on the clothes of the user. The provision of the double rack and pinion movement makes possible the well 65 balanced and symmetrical appearance and operation of the device and eliminates any tendency for the sparking wheel pivoting means to become unevenly worn at the respective sides of the sparking wheel. This is important to insure a 70 smooth and uniform abrasive action against the spring pressed pyrophoric member and to prevent binding and jamming of the sparking wheel or associated parts.

75 It will be noted that the rack and pinion gear ratio is such that the operating thumb button may

be normally positioned at an elevation approximately on a level with the normal position of the snuffer cap, yet when the thumb button is depressed through the available short distance to the top of the fuel receptacle, the snuffer cap is thereby elevated to or beyond a substantially vertical position out of the neighborhood of the flame. Yet the gear ratio is such that the snuffer cap will be firmly urged into seating engagement with the wick tube, thus sealing the protruding wick against the escape of fuel vapors.

It will be further observed that the snuffer and the snuffer carrying members, together with the guard 40 and the pinions 28 and 29 may be formed as shown, as a rugged unitary assembly which is 15 substantially complementary to the thumb piece assembly. The symmetrical spacing and appearance of the wick tube and the plunger 34 further enhance the appearance of the mechanism and its well balanced operation.

20 Many changes may be made in the physical embodiment of the invention with the scope of the appended claims without departing from the spirit thereof.

What I claim is:—

1. A cigar lighter comprising in combination, 25 a fuel receptacle, a wick tube projecting therefrom, a standard mounted on the receptacle adjacent said wick tube, an abradant surfaced wheel journaled in said standard, means for pressing a pyrophoric element against the surface of said wheel, a snuffer element freely journaled on the shaft of said wheel for revolution, a pinion carried by said snuffer element, means longitudinally slidable in said receptacle and projecting therefrom, a rack member rigidly carried by said sliding means in mesh with said pinion, and a pawl carried by said snuffer element spring-pressed into engagement with ratchet teeth carried by said wheel.

40 2. A cigar lighter comprising, in combination, a fuel receptacle, a wick tube opening therefrom, pyrophoric sparking means for igniting fuel carried by a wick housed in said tube, said means comprising an abradant surfaced wheel journaled on a shaft mounted on said receptacle, a pivoted snuffer mounted to oscillate about said shaft, a second tube opening from said receptacle, a plunger reciprocating in said last named tube, a finger piece carried by said plunger, pinion teeth carried by said snuffer, a rack carried by said finger piece transmitting movement thereof to said snuffer in amplified amount and means to transmit movement of said snuffer to said wheel.

45 3. A lighter having in combination a fuel receptacle, an abradant wheel journaled on said receptacle, a pyrophoric member in operative engagement with said wheel, a wick projecting from said receptacle adjacent said wheel, a tubular member extending into said fuel receptacle, a tubular operating member fitting and telescoping within said tubular member, a coil spring housed in said tubular members and tending to eject said operating member from the first tubular member, and means whereby when said operating member 50 is pushed inwardly the wheel is caused to rotate.

55 4. A lighter having in combination a receptacle, an abradant wheel journaled on said receptacle, a pyrophoric member in operative engagement with said wheel, a wick projecting from said receptacle adjacent said wheel, a snuffer for the wick having two side members, one on each side of the wheel, and journaled about the same axis as the wheel, two gears fixed to said side members respectively, a manually pressible member 60

having two racks for operating said gears respectively, and means whereby the wheel is rotated when the snuffer is operated.

5. A lighter having in combination a receptacle, an abradant wheel journalled on said receptacle, a pyrophoric member in operative engagement with said wheel, a wick projecting from said receptacle adjacent said wheel, a snuffer for the wick journalled on the same axis as the wheel, a gear member connected to the snuffer, a rack meshing with said gear member, a manually pressible member for operating said rack, means operatively connecting said wheel and snuffer to rotate the wheel upon elevation of the snuffer, and a tube extending into said receptacle, said manually pressible member having sliding engagement in said tube.

6. A lighter having in combination a receptacle, an abradant wheel journalled on said receptacle, a pyrophoric member in operative engagement with said wheel, a wick projecting from said receptacle adjacent said wheel, a snuffer for the wick having two side members, one on each side of the wheel, and journalled about the same axis as the wheel, two gears fixed to said side members respectively, a manually pressible member having two racks for operating said gears respectively, and means whereby the wheel is rotated when the snuffer is operated, said last mentioned means including a ratchet member rigid with the wheel and a pawl member carried by the snuffer and operatively engaging the ratchet member.

7. A lighter having in combination a receptacle having ears integral with the sides of the receptacle and extending upwardly from the top thereof, an abradant wheel journalled between said ears, a pyrophoric member in operative engagement with said wheel, a wick projecting from said receptacle adjacent said wheel, means for operating the wheel, and a cap plate secured on top of said receptacle beneath the wheel, said cap plate having an opening through which the wick extends and slots through which said ears extend, and said cap plate having a depending flange extending about the upper edge of the receptacle.

8. A lighter having in combination a receptacle, an abradant wheel journalled on top of said receptacle, a pyrophoric member in operative engagement with said wheel, a wick projecting from said receptacle adjacent said wheel, a wick tube secured to the top wall of said receptacle and through which said wick passes, and a cap plate extending over said top wall of the receptacle and beneath said wheel, a tube extending into said receptacle from the top thereof, a member slideable in said tube, and means whereby the wheel is operated when said member is manually pressed, said cap plate having an opening through which said last mentioned member passes.

9. A lighter having in combination a fuel receptacle, an abradant wheel journalled on the receptacle, a pyrophoric member in operative engagement with the wheel, a wick projecting from the receptacle adjacent the wheel, a snuffer for the wick journalled about the same axis as the wheel, and operatively connected thereto, a gear member fixed to the snuffer, a manually operated reciprocating rack member which when manually pushed operates said gear and the snuffer and rotates said wheel, a tubular member located in the fuel receptacle, and a coiled spring situated in said tubular member and acting to return the manually operated member after it has been manually operated to actuate the wheel and snuffer.

10. A lighter construction comprising a fuel receptacle, a wick therefor, pyrophoric lighting means adjacent said wick, actuating means for said pyrophoric lighting means comprising a reciprocating finger piece member, an enclosure integral with said fuel receptacle and within which a portion of said finger piece member is received when pressed to operate the lighting means, pairs of cooperating sliding guide portions carried by the receptacle and on said finger piece member for retaining said member against transverse and rotational movements, and cooperating rack and pinion means on said reciprocating member and said lighting means respectively to transmit actuating motion from said finger piece to said lighting means.

11. A lighter construction comprising a fuel receptacle, a wick therefor, pyrophoric lighting means carried by said fuel receptacle, a reciprocating pressible finger piece member mounted at the side of said lighting means opposite from the wick, rack and pinion means operatively associating said finger piece member and the lighting means, said finger piece member having a cavity and said receptacle carrying a seating portion aligned with said cavity for receiving an elongated spring member for normally maintaining said finger piece in extended position, and a snuffer member operatively associated with the rack means whereby when said finger piece member is pressed said snuffer member is removed from the wick.

12. A lighter construction comprising a fuel receptacle, a wick protruding therefrom, pyrophoric sparking wheel lighting mechanism adjacent the wick on the receptacle, a reciprocating depressible finger piece at the side of said mechanism opposite from the wick, a snuffer cap member pivotally mounted coaxially with said sparking wheel and connected to pinions coaxial with said wheel at each side thereof, said finger piece being provided with a pair of integrally formed rack members coating respectively with said pinions, the periphery of the sparking wheel extending therebetween, said fuel receptacle being provided with a cavity, and said finger piece also being integrally formed with a plunger spring barrel entering said cavity when the finger piece is depressed.

13. A lighter construction comprising a fuel receptacle, a wick and pyrophoric sparking wheel lighting means adjacent thereto on the receptacle, a snuffer cap member pivotally mounted coaxially with said wheel, a ratchet wheel mounted coaxially with the sparking wheel and fixed to rotate therewith, said snuffer cap member comprising in part a guard covering and substantially concealing the sparking and ratchet wheels, a spring pressed pawl mounted within and substantially covered by said snuffer cap member adjacent its wheel guarding portion, and for rotating the wheels when the snuffer cap is elevated, and a spring pressed finger piece member extending to the side of said wheels opposite from the wick, a cavity being formed in a wall of said receptacle for receiving the lower portion of said finger piece member when depressed, said finger piece member being operatively associated with an adjacent portion of said snuffer cap member whereby the snuffer cap is elevated and the sparking wheel is operated upon pressing of said finger piece member.

14. A lighter construction comprising a fuel receptacle, a wick and pyrophoric sparking wheel lighting mechanism adjacent thereto on the re-

- ceptacle, a manually pressible reciprocating finger piece member at the side of said mechanism opposite from the wick, said receptacle carrying a housing telescopically receiving a portion of said finger piece member when pressed, mechanism including a pair of racks on said finger piece member and cooperating pinions at each side of the 5 sparking wheel for operatively connecting said finger piece member and said wheel to rotate the wheel when the finger piece is pressed, and a snuffer cap also operatively associated with said racks whereby the snuffer cap is moved to expose the wick to sparks from the sparking wheel upon operation thereof.
- 15 15. A lighter construction comprising a fuel receptacle, a wick and a pyrophoric sparking wheel lighting mechanism adjacent thereto and carried by the receptacle, a manually pressible reciprocating finger piece member at the side of said mechanism opposite from the wick, a snuffer cap member also carried by the receptacle, rack and pinion means operatively connecting said finger piece member, said lighting mechanism, and said snuffer member, whereby when said finger piece member is manually depressed, the snuffer cap member is elevated and the sparking mechanism is operated, the receptacle carrying an enclosure for telescopically receiving the lower portion of said finger piece member when depressed.
- 20 16. A lighter construction comprising a receptacle, a wick protruding therefrom, pyrophoric sparking wheel lighting means mounted on said receptacle adjacent said wick, a ratchet wheel affixed to said sparking wheel and having teeth protruding from its periphery, a depressible finger piece member on said receptacle at the side of said wheel opposite from said wick, mechanism including a pinion, a reciprocating rack, and pawl means for operatively connecting said finger piece member and said ratchet wheel to rotate the sparking wheel when the finger piece is depressed, said rack being formed on a member slidably carried in a cavity provided in the top wall of said receptacle, and a snuffer cap member formed with a 25 sparking wheel and ratchet guard normally substantially concealing said wheels, and pivotally mounted coaxially with said pinion on the receptacle to be operated upon depression of said finger piece to expose the wick to sparks from said sparking wheel lighting means.
- 30 17. A lighter construction comprising a fuel receptacle, a wick protruding therefrom, pyrophoric sparking wheel lighting mechanism adjacent the wick on the receptacle, a reciprocating finger piece mounted on the receptacle, a snuffer cap member pivotally mounted coaxially with said sparking wheel and having operating members at each side thereof, said finger piece being provided with a pair of plate-like portions coacting respectively with said snuffer operating members and slidably embracing the snuffer cap member whereby operation of the finger piece will operate the wheel and snuffer by manual pressure, and spring restoring means for said finger piece.
- 35 18. In a lighter, a casing, a plunger mounted for reciprocation in a straight line path in said casing, and projecting above the top thereof, a spring acting on said plunger to project it to its uppermost position, a head on said plunger adapted to be depressed by a finger of the user against the action of the spring, supporting means projecting from said casing, a shaft pivoted in said supporting means, an abrading wheel on said shaft, a wick projecting from the top of said casing, a wick snuffing cap, an operating member

pivoted to said shaft carrying said cap, means for operatively connecting said member to the wheel, and means for operatively connecting the plunger head and the cap carrying member whereby depression of the plunger head by direct manual pressure exerted thereon rotates the member to uncap the wick and to operate the abrading wheel.

19. A lighter construction comprising a fuel receptacle member, a wick extending upwardly from said member at one side of the top thereof, a finger piece at the other side of said top depressible into said fuel receptacle member, a rotatable sparking wheel and cooperating pyrophoric means mounted on said top between said wick and finger piece, a sliding rack and pinion means for operating said sparking wheel by depression of said finger piece, and an integrally formed sparking wheel guard and wick snuffer pivotally mounted at said top and operatively associated with said finger piece, whereby depression of the finger piece also raises said snuffer and guard to expose the wick to sparks from said wheel.

20. A lighter comprising a relatively thin substantially rectangular fuel receptacle member having a wick, sparking wheel lighting means, and a depressible finger piece arranged in succession along the top thereof, a rack slidably mounted at the top of said receptacle member, ratchet means and a pinion cooperating with said rack to operatively connect said finger piece and sparking wheel means whereby depression of the finger piece operates the sparking wheel, and an integrally formed sparking wheel guard and wick snuffer member pivotally mounted coaxially with said pinion at said top and operatively associated with said finger piece, whereby depression of the finger piece also raises said snuffer and guard to expose the wick to sparks from said wheel.

25 21. A lighter construction comprising a fuel receptacle, a wick and pyrophoric sparking wheel lighting means adjacent thereto on the receptacle, a snuffer cap member pivotally mounted on the receptacle, a ratchet wheel mounted coaxially with the sparking wheel and fixed to rotate therewith, said snuffer cap member comprising in part a guard covering and substantially concealing the sparking and ratchet wheels, a spring pressed pawl mounted within and substantially covered by said snuffer cap member adjacent its wheel guarding portion, and for rotating the wheel when the snuffer cap is elevated, a finger piece member, means on said receptacle on the side of said wheel remote from said wick mounting said finger piece for downward movement thereon, a coiled spring within said finger piece tending to force the same upwardly, and means whereby upon pressing said finger piece downwardly, said snuffer is elevated from said wick and said wheel is rotated by manual pressure to ignite the wick.

30 22. A lighter construction comprising a receptacle, a wick protruding therefrom, pyrophoric sparking wheel lighting means mounted on said receptacle adjacent said wick, a ratchet wheel affixed to said sparking wheel, a depressible finger piece portion on said receptacle at the side of said wheel opposite from said wick, mechanism including pinion means, a reciprocating rack, and pawl means for operatively connecting said finger piece portion and said ratchet wheel to rotate the sparking wheel when the finger piece is depressed, said rack being formed on a member slidably carried within the top of said receptacle.

- cle, a snuffer cap carried by a sparking wheel and ratchet guard, said guard being pivotally mounted on the receptacle to be operated upon depression of said finger piece to expose the wick to 5 sparks from said sparking wheel lighting means, and a spring member carried within a cavity in said receptacle and acting against said slidable member to resist depression of the finger piece and to react upon said mechanism to hold the 10 snuffer cap and guard yieldingly in closed position.
23. A lighter having in combination a receptacle, an abradant wheel journalled on top of said receptacle, a pyrophoric member, resilient 15 means projecting said pyrophoric member into engagement with said wheel, a wick extending into said receptacle and projecting from the top thereof on one side of the wheel, a hollow finger piece, means on said receptacle on the side of said 20 wheel remote from said wick mounting said finger piece for downward movement theron, a coiled spring within said finger piece tending to force the same upwardly, a snuffer for said wick and means whereby, upon pressing said finger piece downwardly, said wheel is rotated by manual 25 pressure to ignite the wick, and said snuffer is removed from said wick, said means being free from a stop whereby said spring upon release exerts its full force to press said snuffer about said 30 wick and said means comprising a rack upon the finger piece, a gear member operated thereby and a ratchet.
24. Pocket lighter comprising an extinguishing cap, a shaft therefor, an abradant wheel on said 35 shaft, in juxtaposition to said cap, a wick normally covered by said cap, a spring controlled plunger, means controlled by said plunger for raising said cap to uncover the wick, means including said wheel for igniting said wick and 40 adapted to be operated simultaneously with the operation of said cap to uncover the wick, said spring actuated plunger automatically returning the cap into its flame extinguishing position upon its release.
45. 25. A pocket lighter of the class described comprising a casing, a stationary member thereon having an opening in its top, a movable member telescoping endwise into said stationary member, a means for normally holding said movable member in extended position from said stationary member, a wick, an extinguisher cover therefor, a shaft for said cover, means for rotating said cover to elevate the same and uncover the wick upon applying pressure on said movable member, an 50 abradant wheel and flint to ignite the uncovered wick and adapted to operate upon the uncovering of said wick, said means for normally holding the movable member extended adapted to automatically return the parts into their normal 55 position with the wick covered to extinguish the flame upon the release of said movable member.
26. A lighter construction comprising a fuel receptacle, pyrophoric lighting mechanism and a wick mounted on top of said receptacle, a pivoted 60 snuffer member mounted on said receptacle, a finger piece mounted on said receptacle in a position spaced substantially from said wick, separate means extending from opposite sides respectively of said snuffer member to the finger piece for 65 providing dual means operatively interconnecting the snuffer member and finger piece, and means for operating said lighting mechanism upon rotating said snuffer member to a raised position.
70. 27. A lighter construction comprising a fuel receptacle, pyrophoric lighting means mounted 75
- at the mid portion of the top of said receptacle, a wick at one side of said lighting means, a reciprocating finger piece member mounted at the other side of said lighting means at the top of the receptacle, means operatively connecting said finger piece and said lighting means to transmit actuating motion from said finger piece to said lighting means, means fixed to a wall of said fuel receptacle for slidably enclosing and guiding a portion of said finger piece member when the 10 same is pressed to operate the lighting means, a snuffer normally in sealing relationship with the wick, snuffer carrying means operative for moving the snuffer to expose the wick upon actuation of said lighting means, and spring means for restoring the snuffer to wick sealing position and the finger piece to normal position upon release of the finger piece after actuation of the lighting means.
28. A lighter construction comprising a fuel 20 receptacle, a pair of spaced parallel plate-like lugs upstanding from the top of said receptacle at the mid portion thereof, a horizontal shaft mounted in said lugs, pyrophoric lighting means mounted between said lugs and including an 25 abradant wheel carried by said shaft, a wick at the top of said receptacle and at one side of said lighting means, a hollow depressible finger piece at the other side of said lighting means and located at the top of said receptacle, a spring with- 30 in said finger piece tending to force the same upwardly, a wick snuffer member pivotally mounted between said lugs and normally substantially embracing and covering said lighting means, a pawl and ratchet connection interconnecting said 35 lighting means and snuffer member whereby when the snuffer member is elevated to expose the wick, said lighting means is simultaneously operated, and interengaging means carried by said finger piece and snuffer member respectively whereby upon depression of said finger piece the snuffer member is elevated and the lighting means is operated.
29. A lighter construction comprising a fuel 40 receptacle, a pair of spaced parallel plate-like lugs upstanding from the top of said receptacle at the mid portion thereof, a horizontal shaft mounted in said lugs, pyrophoric lighting means mounted between said lugs and including an 45 abradant wheel carried by said shaft, a wick at the top of said receptacle and at one side of said lighting means, a hollow finger piece at the other side of said lighting means and located at the top of said receptacle, means at the side of said wheel remote from said wick mounting said finger piece for downward movement, a wick snuffer member pivotally mounted between said lugs and normally substantially embracing and covering said lighting means, a pawl and ratchet connection interconnecting said lighting means and 50 snuffer member whereby, when the snuffer member is elevated to expose the wick, said lighting means is simultaneously operated, a spring with- 55 in said finger piece tending to force the same upwardly, and interengaging means carried by said finger piece and snuffer member respectively whereby the snuffer member is normally retained in a closed position by the force of said spring.
30. A pyrophoric lighter including a fuel 60 receptacle, a pair of spaced ears extending upwardly from an intermediate portion of the top of said receptacle, a sparking wheel mounted between said ears on a substantially horizontal axis, a pyrophoric member engaging said wheel, a wick 65 protruding through the top of the receptacle on 70

one side of the sparking wheel, a downwardly movable finger piece mounted over the top of the receptacle on the other side of said wheel, a snuffer member also pivoted over the top of the receptacle in said ears and between said finger piece and wick, means for moving the snuffer member upwardly when the finger piece is moved downwardly, a ratchet member turning with the sparking wheel and a pawl member acting between the snuffer member and the ratchet member, whereby the wheel is turned to project sparks onto the wick by the snuffer member when the latter is raised to uncover the wick, said finger piece and its mounting being confined to the space which is on its respective side of the sparking wheel and being provided with a restoring spring urging it toward its normal idle position.

31. A pyrophoric lighter including a receptacle having its side walls free of lighter operating mechanism and adapted to be grasped within the hand of the user, and a wick, sparking wheel and finger piece mounted in a row on the top of the receptacle, the sparking wheel being located between the wick and finger piece and mounted on

a horizontal axis between ears extending upwardly from the top of the receptacle, a snuffer member also pivoted on a horizontal axis above the top of the receptacle, which axis is between the finger piece and the wick, said snuffer member having top and side walls partially enclosing the sparking wheel and a cap adapted to enclose the wick, the finger piece being mounted to move downwardly and upwardly, a restoring spring pressing the finger piece in an upward direction, 5 a pawl and ratchet connection acting between the snuffer and the sparking wheel, said sparking wheel being free of operating connection except through the medium of the snuffer and said pawl and ratchet connection, means whereby 10 upon the downward movement of the finger piece said snuffer member is turned angularly with respect to the wick and finger piece to lift its cap from around the wick, the said snuffer member having a portion adapted to be engaged by a part 15 on the finger piece to hold the snuffer in snuffing position under the action of said restoring spring.

LOUIS V. ARONSON.
